UNITED STATES PATENT OFFICE.

EUGENE M. SCOVILLE, OF CINCINNATI, OHIO, ASSIGNOR OF ONE-HALF TO FLOYD L. SWANBERG, OF PITTSBURGH, PENNSYLVANIA.

SIGHT FEED.

Application filed May 19, 1927. Serial No. 192,770.

This invention relates in general to improvements in sight feeds, and relates more specifically to improvements in the construction and operation of visible flow indicators 5 for liquids such as lubricating oil or the like.

An object of the invention is to provide a new and useful sight feed which is interchangeably cooperable with various types of fluid or liquid supply fittings in order to effectively adapt the feed to a variety of uses. Another object of the invention is to provide a visible flow indicator for liquids such as oil, wherein undesirable escape or 15 leakage of liquid is positively eliminated. A further object of the invention is to provide a compact sight flow device which is simple in construction and highly efficient in operation. Still another object of the invention is to provide a sight feed unit which may be readily manufactured, assembled and dismantled. A further object of the invention is to provide a flow indicating unit which may be conveniently installed and 20 manipulated, and the various elements of which may be quickly adjusted. Another object of the invention is to provide a sight feed lubricator which may be readily inspected and cleaned in order to maintain the same in operating condition, and wherein an 25 emergency source of lubrication may be provided in case the normal source of supply fails. Still another object of the invention is to provide a sight feed which is 30 readily insertable as a unit between an oil supply line and a source of utilization, regardless of the relative position of the supply line outlet and the source inlet. These and other objects and advantages of the 35 improvement will be apparent from the following description.

A clear conception of an embodiment of the invention and of the mode of operating, adjusting and installing devices constructed 45 in accordance therewith, may be had by referring to the drawing accompanying and forming a part of this specification in which like reference characters designate the same or similar parts in the various views.

Fig. 1 is a central vertical section through 50 one of the improved sight feeds, showing the same completely assembled.

Fig. 2 is a side elevation of the assembled sight feed.

Fig. 3 is a top view of the assembled sight feed.

Fig. 4 is a top view of a modified form of fluid distribution fitting adapted for interchangeable application to the sight feed of Figs. 1 to 3.

Fig. 5 is a top view of another form of fluid distribution fitting which is interchangeably applicable to the sight feed.

Fig. 6 is a top view of still another form of interchangeable fluid distribution fitting.

Fig. 7 is a top view of another form of interchangeable applicable fluid distribution fitting.

Fig. 8 is a central section through a modified type of union for attaching the piping 70 to the fluid supply and distributing fittings.

The improved sight feed specifically illustrated in the drawing, comprises in general a main body 2 having lateral side openings; a threaded base 3 detachably associated with 75 the lower portion of the body 2 and adapted for attachment directly to a bearing or the like; a casing 5 pivotally associated with the upper portion of the body 2; clamping structure consisting of a nut 6 having screw thread 80 coaction with the casing 5 and adjustable relatively to the body 2; and one of several different types of fluid distribution fittings 4, 24, 34, 44, 54, interchangeably and reversibly cooperable with the casing 5 between the body 85 2 and the nut 6. Resting upon the base 3 within the body 2, is a tubular transparent member 11 the upper end of which is normally engaged by a centrally perforated annular retaining cap 10. The cap 10 is constantly urged in a downward direction 90 against the member 11 by means of a helical spring 15 the upper end of which reacts against the lower end of the casing 5, and the transparent member 11 may be freely re- 95 moved through the lateral openings of the body 2 when the cap 10 is raised against the action of the spring 15. When the transparent member 11 has been removed, the downward movement of the cap 10 is limited 100 by means of stop pins 28 secured to the body 2, these pins also serving to center the member 11.

The upper portion of the body 2 is provided with internal abutment surfaces 19 105 which are engaged by an annular flange or lugs formed integral with the lower end of the casing 5, this coaction being such that

the casing 5 is pivotally confined within the upper portion of the body 2. The casing 5 is provided with a central vertical passage 17 the upper end of which communicates with a threaded socket and the lower discharge end of which is in vertical alignment with the final discharge passage 21 of the base 3. The upper threaded socket of the casing 5 may either be sealed by means of a pipe plug 7 as shown, or may be provided with an emergency oil cup for delivering oil directly to the bearing or other source of utilization through the passages 17, 21, in case the normal source of supply fails. The casing 5 is also provided with an annular external recess 16 which is communicable with the central passage 17 through a lateral port 45.

Each of the fluid supply and distributing fittings 4, 24, 34, 44, 54, is provided with one or more radially disposed threaded openings 23, and with a central bore 26 adapted to snugly fit the external cylindrical surface of the casing 5 and to thus inclose the recess 16. The fittings 4, 24, 34, 44, 54 are also provided with threaded bosses 25 each formed for the reception of a needle valve 14 as shown in Fig. 1, the needle valve being adjustable by means of a hand wheel 22 and having an inner pointed end cooperable with the port 45 to control the flow therethrough. The fittings 4, 24, 34, 44, 54 are moreover provided with oppositely disposed chamfers 27 adjacent to the bores 26, these chamfers being filled with suitable packing material in the assembled structure. The threaded bosses 25 of the fittings are additionally provided with packing elements 18 for sealing the joint around the needle valve 14.

Each of the threaded openings 23 is formed for the interchangeable reception of either a union 12 such as shown in Fig. 1, or a union 13 as shown in Fig. 8. When the coupling type of union 12 shown in Fig. 1 is employed, the supply and discharge pipes 9 may be attached to the unions 12 by means of pipe couplings 8. When the threaded type of union 13 shown in Fig. 8 is employed, the supply and discharge pipes may be attached directly to the threaded sockets of the unions in an obvious manner.

Of the five different types of fittings 4, 24, 34, 44, 54, the fitting 4 is of the single symmetrical type wherein the single opening 23 is in direct alignment with the boss 25. The fitting 54 is of the single type wherein the opening 23 extends at right angles relative to the axis of the boss 25. The fitting 44 is of the double symmetrical type wherein the oppositely disposed aligned openings 23 are disposed at right angles to the axis of the boss 25, and the fitting 34 is of the double type wherein one opening 23 is in alignment with the axis of the boss 25 while the

other opening 23 extends at right angles thereto. The fitting 24 is of the three way type wherein one opening 23 is disposed in direct alignment with the boss 25 while the other two opposed openings 23 are in alignment with each other but extend at right angles to the boss axis. All of these fittings are interchangeably and reversibly cooperable with a common casing 2.

When assembling the sight feed, the casing 5 is first slipped through the lower end of the body 2 after which the spring 15, cap 10 and pins 28 are successively applied to maintain these elements in assembled relation. The base 3 may then be attached to the body 2 after which the transparent member 11 may be inserted between the base 3 and the cap 10. Any one of the fittings 4, 24, 34, 44, 54 may then be slipped over the upper end of the casing 5, and the clamping nut 6 subsequently applied to lock the fitting against the body 2 with the axis of the boss 25 in alignment with the port 45, suitable packings having been previously applied in the chamfers 27. The pipe plug 7 and needle valve 14 may then be applied in an obvious manner thus completing the assemblage of the sight feed. The installation of the sight feed may readily be effected by attaching the base 3 to the bearing and by attaching the supply and discharge pipes 9 to the fitting which embraces the casing 5. If the opening 23 of the fitting is not properly directed to accommodate attachment of the supply pipe 9, after attachment of the base 3 to the bearing, the clamping nut 6 may be released thereby permitting free angular adjustment of the distributing fitting about the casing 5.

During normal operation of the sight feed when utilizing a single fitting 4, 54, the entire supply of oil is admitted from the supply pipe 9 to the recess 16 and is delivered in controllable quantities past the needle valve 14 to the passage 17 from whence it gravitates through the transparent member 11 to the bearing through the discharge passage 21. All of the oil admitted to the recess 16 is thus delivered to the single bearing when the single fittings are employed, and the member 11 provides a visible indication of the rate of feed. When utilizing either of the multiple fittings 24, 34, 44, only a portion of the oil supplied to the recess 16 of the casing 5, is delivered through the port 45 thereof, the remainder of the oil supplied being discharged through the openings 23 other than that being utilized as a supply opening, and which other openings may be connected to other sight feeds associated with additional bearings of a group. If it is not desired to utilize one or more of the openings 23 of a multiple fitting, such opening or openings may be sealed by means of a pipe plug 7 cooperating with a union, and

an emergency oil cup may be provided in substitution for the closure plug at the top of the casing 5, whenever desired. The reversibility of the fittings is especially useful when employing fittings 34, 54 as shown in Figs. 6 and 4. These fittings 34, 54 may be reversed with respect to the casing 5 in order to accommodate connection thereof to supply or distribution pipes 9 disposed at right angles to each other or to the axis of the needle valve 14, in an obvious manner, and thus eliminate necessity of providing right and left hand fittings.

From the foregoing description it will be apparent that the improved sight feed while being extremely simple and compact in construction, is also highly flexible as to installation and adjustment. The device is moreover exceedingly efficient in operation and may be readily assembled and dismantled. The transparent member 11 may be conveniently removed or applied while the sight feed is in operation, and the packings effectively prevent undesirable escape of oil. The reversibility and interchangeability of the fittings 4, 24, 34, 44, 54 reduces to a minimum the number of stock parts required and the angular adjustment of the fittings greatly facilitates installation of the sight feed. The unions 12, 13 also enhance the flexibility of the unit and enable the use of any desirable form of piping.

It should be understood that it is not desired to limit the invention to the exact details of construction and operation herein shown and described, for various modifications within the scope of the claims may occur to persons skilled in the art.

It is claimed and desired to secure by Letters Patent:—

1. In combination, a body having a normally visible interior, a transparent member confined within said body, a casing carried by and having passages communicating with the interior of said body, clamping structure adjustably coacting with said casing, and a fitting embracing said casing and adjustably retained in position by said body and said clamping structure.

2. In combination, a body having a normally visible interior, a transparent member confined within said body, a casing rotatable relative to and having passages communicating with the interior of said body, clamping structure coacting with said casing and adjustable relatively to said body, and a fitting embracing said casing between said body and said clamping structure.

3. In combination, a body having a normally visible interior, a transparent member confined within said body, a casing carried by said body, and resilient means cooperating with said casing and with said member to retain said member in position within said body.

4. In combination, a body having opposite side openings, a transparent tubular member located within said body and removable through one of said openings, a casing coacting with said body above said openings, and a spring cooperating with said casing and with said member to resiliently retain said tube in position, said tube being removable through said opening by compressing said spring.

5. In combination, a body having a side opening, a transparent tubular member covering said opening, a casing pivotally associated with said body and having internal passages, means for controlling the flow of fluid through said passages to said body, clamping structure adjustably associated with said casing, and a fitting for introducing liquid to said casing, said fitting being adjustably retained in position by said body and said clamping structure.

6. In combination, a body having a side opening, a transparent member covering said opening, a casting rotatably attached to said body above said opening, said casing having passages communicating with the interior of said body, a fitting pivotally supported by said body and embracing said casing, and a needle valve carried by said fitting and adjustable relative to said casing to control the flow of liquid through said passages.

7. In combination, a body having a side opening, a casing rotatable relative to the upper portion of said body, a transparent tubular member located within said body and removable through said opening, a cap coacting with the top of said member, and a spring coacting with said casing and with said cap to retain said member in position.

8. In combination, a body having a side opening, a base secured to said body below said opening, a casing secured to said body above said opening, a transparent tubular member resting upon said base within said body, a cap resting upon said member adjoining said opening, and a spring coacting directly with said cap and with an end of said casing.

9. In combination, a body having a side opening, a base secured to the bottom of said body, a casing rotatable relative to the top of said body, a transparent member resting upon said base, a cap resting upon said member, a spring coacting with said cap and with said casing, and a fitting angularly adjustably coacting with said casing and with said body.

10. In combination, a hollow body having a side opening, a transparent member covering said opening, a casing secured to the upper portion of said body, said casing having a through passage directed toward said body and also having a laterally extending passage, removable means for normally sealing the upper end of said through passage,

4
and a fitting embracing said casing and providing a liquid supply conduit communicating with said lateral passage.

11. In combination, a body having an opening and an interior normally visible through said opening, a transparent member covering said opening, a casing carried by and having passages communicating with the interior of said body, clamping structure adjustably carried by said casing, and a fluid supply fitting reversibly cooperable with said casing and adjustably retained in position by said body and said clamping structure.

12. In combination, a body having a normally visible interior, a casing pivotally associated with and having passages communicating with the interior of said body, clamping structure adjustably carried by said casing, and a fluid supply fitting reversibly co-

operable with said casing and angularly adjustably retained in position by said body and said clamping structure, said fitting having at least two fluid conducting passages radiating from the central axis of said casing.

13. In combination, a body having an opening, a transparent member covering said opening, a casing carried by and having passages communicating with the interior of said body, clamping structure adjustably co-acting with said casing, and a plurality of fittings interchangeably cooperable with said casing between said body and said clamping structure.

In testimony whereof, the signature of the inventor is affixed hereto.

EUGENE M. SCOVILLE.
